UNITED STATES PATENT OFFICE.

CHARLES E. BOWN, OF BATTLE CREEK, MICHIGAN, ASSIGNOR TO BOWN MACHINE COMPANY, LTD., OF BATTLE CREEK, MICHIGAN.

TOOL-HOLDER.

No. 911,537.

Specification of Letters Patent.

Patented Feb. 2, 1909.

Application filed March 9, 1906. Serial No. 305,270.

To all whom it may concern:

Be it known that I, CHARLES E. BOWN, a citizen of the United States, residing at Battle Creek, county of Calhoun, State of Michigan, have invented certain new and useful Improvements in Tool-Holders, of which the following is a specification.

This invention relates to improvements in tool holders.

10 The objects of this invention are, first, to provide an improved tool holder which may be adjusted to hold the tool at any desired angle. Second, to provide an improved tool holder embodying these advantages which 15 may be quickly and easily adjusted to the desired position.

Further objects, and objects relating to structural details, will definitely appear from the detailed description to follow.

20 I accomplish the objects of my invention by the devices and means described in the following specification.

The invention is clearly defined and pointed out in the claim.

25 A structure embodying the features of my invention is clearly illustrated in the accompanying drawing forming a part of this specification, in which—

30 Figure 1 is a plan of a structure embodying the features of my invention. Fig. 2 is a detail vertical section partially in section, taken on a line corresponding to line 2—2 of Fig. 1. Fig. 3 is a detail partially in section, taken on a line corresponding to line 35 3—3 of Fig. 2.

In the drawings, the sectional views are taken looking in the direction of the little arrows at the ends of the section lines, and similar letters of reference refer to similar 40 parts throughout the several views.

Referring to the drawings, A represents the tool post of a lathe in which the shank B of my improved tool holder is shown clamped. On the forward end of the shank B is a 45 clamping head B'. This clamping head is provided with a concaved seat B'' in its upper face, and is also provided with a transverse opening B''' therethrough. This transverse opening is preferably centrally ar-

ranged in regard to the seat. I arrange 50 through this opening in the clamping head B an adjustable clamping member C. This clamping member C has a longitudinal slot C' therein and a head C'' at its upper end. On its lower end is a nut c', by means of 55 which it is retained in the clamping head B'.

A tool supporting block D is arranged 60 through the slot in the adjustable member C and serves as a rest or support for the tool as E, which is also arranged through the slot. The block D is shaped on its under side to fit the concave seat in the clamping head B', as clearly appears from the drawing. This block is provided with a lug D' 65 on its under side which projects into the opening B''' in the head, thereby limiting the adjustment of the block. By adjusting this block, the angle of the tool in relation to the horizontal plane is controlled. By means of the member C, the tool may be adjusted to either side. It is evident that these 70 adjustments may be very accurately made to secure any desired angle, taking into consideration, of course, the scope of the particular device. Set screws c are arranged 75 through the head of the clamping member C and are adapted to engage the top of the tool, these clamping all the adjustable parts in position.

It is evident that my improved tool holder 80 is very simple in construction and is capable of very quick and easy adjustment. I have illustrated the same in detail in the form preferred by me, although I am aware that it is capable of considerable variation without departing from my invention.

Having thus described my invention, what I claim as new and desire to secure by Letters Patent, is:

In a tool holder, the combination with a 90 clamping head, having a spherically concaved seat therein and a transverse opening therethrough, located centrally of said seat; an adjustable clamping member having a longitudinal slot therein, arranged in said 95 opening through said clamping head; a block shaped on its under side to fit said concaved seat in said clamping head, and

having a lug thereon projecting into said opening therein, arranged through the slot in said adjustable clamping member; and a pair of set screws carried by said adjustable clamping member adapted to engage a tool arranged on said block for clamping the parts in their adjusted positions.

In witness whereof, I have hereunto set my hand and seal in the presence of two witnesses.

CHARLES E. BOWN. [L. s.]
